UNITED STATES PATENT OFFICE.

ALEXANDER BOGDÁNFFY, OF BROOKLYN, NEW YORK.

DISK-CUTTING MACHINE.

1,307,077.

Specification of Letters Patent. Patented June 17, 1919.

Application filed August 10, 1917. Serial No. 185,492.

To all whom it may concern:

Be it known that I, ALEXANDER BOGDÁNFFY, a former subject of the King of Hungary, and who have declared my intention of becoming a citizen of the United States, and a resident of Brooklyn, in the county of Kings and State of New York, have invented certain new and useful Improvements in Disk-Cutting Machines, of which the following is a specification.

The invention relates to machinery employed in connection with the manufacture of closures, for example of the character of the so-called crown corks, and pertains more especially to a machine for cutting out the disks of cork or similar material with which said crown corks are lined.

The invention has for its object to provide a machine designed to receive the cork in the form of strips or sheets, and to cut therefrom in a simple and expeditious manner, and with a minimum of operations, disks of the desired diameter. A further object of the invention resides in the manner of presenting the material to the cutters for the cutting out of the disks, and whereby the use of special ejecting means may be dispensed with, the arrangement, furthermore, being such that the cutters may be readily sharpened and adjusted. A still further object of the invention consists in a positive feeding means for advancing the cork strip with reference to the cutters.

In the accompanying drawings, which illustrate the invention—

Figure 1 is a front elevation of the machine, a portion thereof being shown in vertical section.

Fig. 2 is a plan thereof, a portion of the mechanism being removed to disclose the supporting platform and cutters.

Fig. 3 is a side view.

Fig. 4 is an end view with a portion of the apparatus omitted.

Fig. 5 is a detail view illustrating the feeding and cutting mechanism.

Similar characters of reference designate corresponding parts throughout the several views.

Referring to the drawings, 10 designates a suitable supporting structure having a platform 11 at one end, and in which are rotatably mounted a plurality of tubular cutters 12 for effecting the cutting out of circular cork disks of the desired diameter.

from strips of natural cork or other suitable material as the same is received from a slicing or similar machine (not shown). These cutters are axially immovable with reference to said platform and structure, and are 60 spaced preferably two in front and one in back and between the two said forward cutters, whereby three disks will be simultaneously cut out by each unit. In the mechanism herein illustrated, two units are shown, 65 being exact duplicates; but it is to be understood that the invention is not restricted to any particular number of said units, and the operation of but one such unit will be considered herein. These cutters may be of 70 any well-known or special design, and are rotated from a suitable source of power (not shown) through pulleys 14 and 14' and belt 15, spools 16 being provided on said cutters to receive the said belt. No claim is made 75 to the manner of driving these cutters as well as their particular construction; but it is believed novel to mount them in fixed relation to the supporting structure.

To the supporting structure 10, at its opposite end, is pivotally secured, as on the shaft 20, a supporting frame or arm, or rather a pair of arms, 21, which carries the entire material-retaining and feeding mechanism. These mechanisms are so arranged 80 that when the frame 21 is swung into the normal position, shown in Fig. 3 of the drawings, the various mechanisms will be in proper relationship to the cutters for effecting the cutting out of the cork disks 90 from the material retained thereby. These disks, when thus cut from the material, will drop through the tubes by the action of gravity; or, in case the location of the tube is such that the disks will stack therein, the 95 said disks will be gradually forced outwardly as they accumulate. Furthermore, should it be desired to sharpen these tubular cutters, the same are rendered readily accessible for this purpose by merely raising 100 the frame 21, the entire mechanism moving about the shaft 20 and being lifted off the platform 11 which retains the said cutters.

The mechanism for retaining the cork material 25, Fig. 5, in position to present it 105 to the cutters consists essentially of a member composed of a lower plate or table 26 having circular perforations 27 therein registering with the edges of the cutters, but normally slightly beyond same, and of the 110

- desired diameter of disks to be cut. The plate 26 is movably mounted on rods 28 and has lateral upturned portions 29 which serve to guide the cork material as well as a further plate or member 30, also mounted upon said rods but fixedly secured thereto, the spacing between said two plates being adjusted for the normal thickness of the material from which the disks are to be cut.
- 10 This plate 30 may be secured in any convenient manner to the rods 28, and the spacing between the two plates is insured by means of suitable washers 31 interposed between the rod-engaging portions of the said two plates. Furthermore, in order to accommodate for irregularities in the thickness of the material, the lower plate 26 is yieldingly held to the plate 30 as by means of springs 32 coiled about the lower ends of said rods, one end of a spring bearing against said plate, and the other against a suitable stop or pin 33 of said rods. It will be noted, thus, that the upper plate 30 is in fixed relationship to the cutters and rods.
- 15 and movable only as a unit with the latter relatively to the former, whereas the lower plate 26 may yield relatively to said cutters independently of the movement of the rods. The upper plate, furthermore, is provided 20 with a longitudinal slot 35 along its median line and carries a cam-engaging surface 36. The rods 28, themselves, are movable as a whole with the two plates and members carried thereby when the cam surface of the 25 upper plate is engaged by a suitable cam, as hereinafter set forth, to depress the said retaining member toward the cutters to effect the cutting out of the disks from the material retained between the said plates. To re-
- 30 store the retaining member to normal position, shown in Fig. 1 of the drawings, when the cam pressure is released, springs 37 are coiled about the upper portions of said rods and bear against pins 38 at one end thereof, and flanged lower extensions 21' of the frame 21 at the other.
- 35 For the purpose of effecting this cutting out action, a cam 40 is rotatably mounted in the frame 21, and is located preferably midway between the two rods 28, and in such position as to cause its surface to engage the cam surface 36 of the upper plate at the proper time, that is to say, when the cork material is in position over the cutters. The entire material-retaining means are thereby moved or depressed sufficiently to bring the material into contact with the cutter edges, and to cut out therefrom the 40 disks which are received by the said tubular cutters to be discharged therefrom. In the embodiment herein set forth, three disks will be simultaneously cut from each unit by the action hereinbefore disclosed, effecting a very rapid production of the disks and with a minimum waste of the material. The piv-

oted frame 21 carrying the mechanism hereinbefore described is of sufficient weight, or may be locked to the supporting structure 10, to resist the upward reaction of the cam shaft when the cam 40 engages the cam-engaging surface 36 to depress the work toward and against the cutters. In the position indicated in full lines, Fig. 5, the material-retaining mechanism is in position to be depressed, and the same will occur as soon as the cam 40 comes into contact with the cam-engaging surface 36; and the period of this depression is properly timed by suitably proportioning the cam, whereupon the pressure is released and the parts restored to the position shown. It then becomes necessary for new material to be fed through the retaining plates; and for this purpose, a gripping member 41 is mounted to be reciprocated in the slots 35 of the upper plate, said gripping member consisting, for example, of a longitudinal channel bar with toothed under-surface, the teeth thereof being located in such proximity to the material as to afford, normally, a sufficient frictional hold thereon when the parts are in position as indicated in Fig. 5. Of course, when the material is being cut out, the same will be separated a certain distance from the gripping member. This separation is maintained during the period of outward movement of the gripping member, which latter is effected by securing said gripping member to a frame or support 42 having lateral guides 43 mounted in ways 44 of the frame 100 extensions 21'. The gripper frame is provided with a portion 45 at its outer end, having preferably a cam-engaging surface 46 which is designed to be acted upon by the cam 40 to move the frame outwardly to the extreme position shown in dotted lines, Fig. 5. As the separation between the gripping member and the cork material then no longer exists, due to cam 40 leaving the surface 36, the gripper secures a sufficient hold on said material to advance the same through the retaining member as the said cam 40 continues to rotate, and its surface engages with a portion 47 of frame 42 and located oppositely to the portion 46, or rather with a cam-engaging portion 48 mounted therein. The cam, by acting on the surface 48, eventually restores the gripper-carrying frame to the position indicated in full lines, and thus feeds forward a predetermined amount of the material, presenting a new surface to the cutters, whereupon the cycle is repeated.

I claim:

1. In a machine for cutting disks of cork strips or sheets: the combination with a frame and a rotary tubular cutter mounted therein; of a member to retain said material; and means to move said member in the axis of said cutter to cut the material, said member and moving mechanism being piv-

totally secured as a whole to said frame so as to be capable of being swung away to expose the cutter.

2. In a machine for cutting disks of cork strips or sheets: the combination with a frame, and a rotary tubular cutter fixedly carried thereby; of retaining means for the cork material; and feeding mechanism to advance the cork material with reference to 10 said cutter, said retaining means and feeding mechanism being pivotally attached to said frame and separable from said cutter.

3. In a machine for cutting disks of cork strips or sheets: the combination with a rotary tubular cutter; of a member to retain said material; means to move said member in the axis of said cutter; means to advance the strip of cork material with reference to 15 said cutter; and a cam common to said retaining member and said feeding means to depress the former and advance and retract the latter.

4. In a machine for cutting disks of cork strips or sheets: the combination with a rotary tubular cutter; of means to retain the cork material; a rotatable cam mounted to engage said retaining means to depress the same toward said cutters; a reciprocable frame mounted above said retaining means; 20 a gripping device carried thereby and movable through a slot of said retaining means, said frame being reciprocable relatively to said retaining means through the action of said cam.

5. In a machine for cutting disks of cork strips or sheets: the combination with a rotary tubular cutter; a retaining member comprising a lower plate perforated to register with the cutter, and a slotted upper 30 plate, the cork material being adapted to be retained and guided between said two plates, and the lower plate being yieldably mounted with reference to the upper plate; strip-advancing means adapted to act through the 40 slot of the upper plate; and means to depress said two plates as a whole in the direction of said cutter to cut out the cork disks from the material retained thereby.

6. In a machine for cutting disks of cork strips or sheets: the combination with a rotary tubular cutter; a retaining member comprising a lower plate perforated to register with the cutter, and a slotted upper plate, the cork material being adapted to be 50 retained and guided between said two plates, and the lower plate being yieldably mounted with reference to the upper plate and both plates being resiliently supported over said cutter; strip-advancing means adapted to 55 act through the slot of the upper plate; and means to depress said two plates as a whole in the direction of said cutter to cut out the cork disks from the material retained thereby.

7. In a machine for cutting disks of cork

strips or sheets: the combination with a frame, and a rotary tubular cutter fixedly mounted therein; a second frame; a retaining member comprising a plurality of vertically movable rods mounted in said second frame; an upper retaining plate secured to 70 said rods and longitudinally slotted; coiled springs mounted about said rods between said plate and said second frame; a perforated plate mounted upon said rods beneath 75 said upper plate and separated therefrom; and coiled springs mounted about said rods, one end bearing against said lower plate and the other being secured to the rods, to yieldingly support the lower plate with reference 80 to the upper plate; a gripper frame movable in said second frame over said retaining member and carrying a suitable gripper member movable in the said slot of the upper plate; and a cam member to depress 85 said two plates as a whole and advance and retract said gripper frame.

8. In a machine for cutting disks of cork strips or sheets: the combination with a frame, and a rotary tubular cutter fixedly 90 mounted therein; a second frame pivotally attached to said first-named frame; a retaining member comprising a plurality of vertically movable rods mounted in said second frame; an upper retaining plate secured 95 to said rods and longitudinally slotted; coiled springs mounted about said rods between said plate and said second frame; a perforated plate mounted upon said rods beneath said upper plate and separated 100 therefrom; and coiled springs mounted about said rods, one end bearing against said lower plate and the other being secured to the rods, to yieldingly support the lower plate with reference to the upper 105 plate; a gripper frame movable in said second frame over said retaining member and carrying a suitable gripper member movable in the said slot of the upper plate; and a cam member to depress 110 said two plates as a whole and advance and retract said gripper frame.

9. In a machine for cutting disks of cork strips or sheets: the combination with a frame, and a rotary tubular cutter fixedly 115 mounted therein; a second frame; a retaining member comprising a plurality of vertically movable rods mounted in said second frame; an upper retaining plate secured to said rods and longitudinally slotted; coiled 120 springs mounted about said rods between said plate and said second frame; a perforated plate mounted upon said rods beneath said upper plate and separated therefrom; and coiled springs mounted about said rods, one end bearing against said lower plate 125 and the other being secured to the rods, to yieldingly support the lower plate with reference to the upper plate; a gripper frame movable in said second frame over said re- 130

taining member and carrying a bar having a roughened lower edge normally in engagement with the material in said retaining member and movable in the said slot of the upper plate; and a cam member to depress said two plates as a whole and advance and retract said gripper frame.

10. In a machine for cutting disks of cork strips or sheets: the combination with a frame, and a rotary tubular cutter fixedly mounted therein; a second frame; a retaining member comprising a plurality of vertically movable rods mounted in said second frame; an upper retaining plate secured to said rods and longitudinally slotted; coiled springs mounted about said rods between said plate and said second frame; a perforated plate mounted upon said rods beneath said upper plate and separated therefrom; 15 and coiled springs mounted about said rods, one end bearing against said lower plate and the other being secured to the rods, to yieldingly support the lower plate with reference to the upper plate; a gripper frame movable in said second frame over said retaining member, carrying a suitable gripper member movable in the said slot of the upper plate, and the upper plate being provided with a cam-engaging surface extending through said gripper frame; and a cam member to depress said two plates as a whole and advance and retract said gripper frame.

Copies of this patent may be obtained for five cents each, by addressing the "Commissioner of Patents, Washington, D. C."

11. In a machine for cutting disks of cork strips or sheets: the combination with a frame, and a rotary tubular cutter fixedly mounted therein; a second frame; a retaining member comprising a plurality of vertically movable rods mounted in said second frame; an upper retaining plate secured to said rods and longitudinally slotted; coiled springs mounted about said rods between said plate and said second frame; a perforated plate mounted upon said rods beneath said upper plate and separated therefrom; 45 and coiled springs mounted about said rods, one end bearing against said lower plate and the other being secured to the rods, to yieldingly support the lower plate with reference to the upper plate; a gripper frame movable in said second frame over said retaining member and carrying a suitable gripper member movable in the said slot of the upper plate; and a cam member to depress said two plates as a whole and advance and 50 retract said gripper frame, which has oppositely-disposed surfaces adapted to be engaged by said cam, and the upper plate being provided with a cam-engaging surface disposed between said gripper frame 55 surfaces.

Signed at New York in the county of New York and State of New York this 8th day of August, A. D. 1917.

ALEXANDER BOGDÁNFFY.
